United States Patent Office

Des. 181,191
Patented Oct. 15, 1957

181,191

SWEATER

Barnett D. Gordon, Manchester, N. H., assignor to
M. K. M. Hosiery Mills, Inc., Boston, Mass., a corporation of Massachusetts

Application August 7, 1956, Serial No. 42,536

Term of patent 14 years

(Cl. D3—4)

The back of the sweater is conventionally plain.
I claim:

The ornamental design for a sweater, as shown and described.
